UNITED STATES PATENT OFFICE.

GEORGE W. LISK, OF CLIFTON SPRINGS, NEW YORK.

PAIL-BOTTOM.

SPECIFICATION forming part of Letters Patent No. 374,687, dated December 13, 1887.

Application filed October 17, 1887. Serial No. 252,610. (No model.)

To all whom it may concern:

Be it known that I, GEORGE W. LISK, of Clifton Springs, in the county of Ontario and State of New York, have invented a new and 5 useful Improvement in Pail-Bottoms, which improvement is fully set forth in the following specification and shown in the accompanying drawings.

Tin pails, when used for holding water, are 10 apt to quickly rust at the bottom, more particularly at or about the joint between the bottom and the side of the pail. This corrosion, it has been found, can be very much retarded, if not wholly prevented, by adding to the pail- 15 bottom a sheet or mass of different metal—as zinc or copper—which in the presence of water or dampness causes a mild electric action to take place, this preventing to a large degree the oxidation of the tin.

20 My invention relates to an improvement in means for attaching and holding a disk of zinc or other metal different from the metal of which the pail is made to the bottom of the pail for the purpose of preventing the corrosive action above referred to, the invention being 25 hereinafter fully described, and more particularly pointed out in the claims.

Referring to the drawings, Figure 1 is a plan of the inner surface of the bottom of a tin pail, 30 showing my improvement, parts being broken away to better show the joint; Fig. 2, a side elevation of a portion of the pail, a part at the bottom being broken away and the bottom plate with other parts diametrically sectioned; 35 Fig. 3, a transverse section of the joint between the pail-bottom and the holder for the metal disk, drawn to a much larger scale for the purpose of more clearly showing the arrangement of the parts; and Figs. 4 and 5, 40 modifications in the manner of forming the joint between the bottom of the pail and the plate beneath it for holding the disk, said figures being drawn to the same scale to which Fig. 3 is drawn.

45 Referring to the parts shown in the drawings, A is a tin pail substantially of common construction, B being the bottom thereof, made of sheet-tin. The bottom is formed with a circular concentric opening, b, the edge of the 50 tin around said opening being turned back to form a burr, d, encircling the opening.

a is a circular plate of tin, having its edge turned to form a burr, e, to be locked with the burr d of the pail-bottom.

c is a circular disk of zinc or some metal 55 other than the kind of which the pail-bottom is made, of such a diameter as to have its periphery meet the inner surface, h, of the burr e of the plate a, which plate serves to hold said disk concentrically in place and against the 60 burr d of the pail-bottom.

By this construction the zinc disk c is protected from wear or damage at the under side of the pail-bottom, and is at the same time in actual contact with the bottom of the pail and 65 the holding-plate a, so that electrical action may at any time take place between the three parts joined—that is to say, the parts B, c, and a. When put together, the seam or joint i, formed by the plates B and a, is hammered or pressed 70 in a vertical direction, causing the parts at the joint to be brought firmly together, and common solder, f, may be run into the creases of the joint both without and within the pail.

I prefer to form the pail with a foot, g, which 75 prevents the part a from coming in contact with the floor or other surface when the pail is set down.

In the form shown in Fig. 4 there are no burrs formed on the bottom of the pail and the holding-plate a, the latter having an offset part or flange, k, to surround the disk, said offset part touching the pail-bottom and soldered thereto, as shown.

In the form shown in Fig. 5 the offset part 85 k is formed on the pail-bottom, the holding-plate a being a mere circular disk soldered to the bottom of the pail.

What I claim as my invention is—

1. In combination with a metal pail-bottom 90 formed with a circular opening therethrough, a circular disk formed of a different metal from that of which said pail-bottom is formed, placed concentrically against or over said opening in the pail-bottom, and a circular holding-plate placed to cover said disk and soldered at its periphery to said pail-bottom. 95

2. In combination with a metal pail-bottom formed with a circular opening therethrough, a circular disk formed of a different metal 100 from that of which said pail-bottom is formed, placed concentrically over said opening in the

pail-bottom, and a circular holding-plate placed to cover said disk, said holding-plate being of larger diameter than said disk and soldered to said pail-bottom beyond the periphery of said disk.

3. A metal bottom for a pail, formed with a circular opening, the latter having its edge folded over to form a burr, in combination with a circular disk formed of a different metal from that of which said pail-bottom is formed, placed concentrically over said opening in the pail-bottom and against said burr, and a circular holding-plate for said disk, having its edge formed into a burr to interlock with the burr of said bottom of the pail, said disk being held between said holding-plate and the burr of the pail-bottom.
- 15 4. A metal bottom for a pail, formed with a

circular opening, the latter having its edge folded over to form a burr, in combination 20 with a circular disk formed of a different metal from that of which said pail-bottom is formed, placed concentrically over said opening in the pail-bottom and against said burr, and a circular holding-plate for said disk, having 25 its edge formed into a burr to interlock with the burr of said bottom of the pail, the inner curved surface of the burr of said holding-plate forming a bearing for the periphery of said disk and serving to prevent lateral motion of the latter.
